UNITED STATES PATENT OFFICE.

LOUIS HOLABIRD, OF CHICAGO, ILLINOIS.

DESIGN FOR A BICYCLE WRENCH AND SCRAPER.

SPECIFICATION forming part of Design No. 28,871, dated June 14, 1898.

Application filed April 4, 1898. Serial No. 676,472. Term of patent 3½ years.

To all whom it may concern:

Be it known that I, LOUIS HOLABIRD, a citizen of the United States, residing at Chicago, county of Cook, State of Illinois, have invented and produced a new and original Design for a Bicycle Wrench and Scraper, of which the following is a specification, reference being had to the accompanying drawings, forming a part thereof.

In the drawings, Figure 1 is a plan view of my design, and Fig. 2 is a cross-section.

As shown in the drawings, the general outline of my design is a circular disk. It is, however, broken by a semicircular line *a* drawn inwardly from the peripheral line of the disk to near the center thereof. It is also broken by the inwardly and obliquely extending lines *b*, the same being nearly parallel and close together, also by the straight lines *c* within the

peripheral line of the disk, which form three 20 sides of a square, also by the straight lines *d*, which form four sides of a hexagon, also by the straight and curved lines *d' d''*, and the similar straight and curved lines *e e'*, all within the peripheral lines of the said disk, and 25 each pair of straight lines being parallel, as shown.

Having described my invention, what I claim and desire to secure by Letters Patent is—

The design for a bicycle wrench and scraper substantially as herein shown and described.

In testimony whereof I affix my signature in presence of two witnesses.

LOUIS HOLABIRD.

Witnesses:

J. BUEHLER,
L. HANKE.
